Specification for Design.

Patented Mar. 9, 1920.

Application filed March 21, 1919. Serial No. 284,214. Term of patent 7 years.

To all whom it may concern:

Be it known that I, JAMES PRINGLE COCHRANE, a subject of the King of Great Britain and Ireland, and a resident of Edinburgh, Scotland, (whose postal address is Murano Works, Albert street, Edinburgh, Scotland,) have invented a new, original, and ornamental Design for an Exposed Pad for the Soles of Boots and Shoes, of which the following is a specification, reference being had to the accompanying drawing, forming part thereof.

The figure is a perspective view of a pad

for the soles of boots and shoes embodying my new design.

I claim:

The ornamental design for a pad for the soles of boots and shoes, as shown.

In testimony whereof I have signed my name to this specification, in the presence of two subscribing witnesses.

JAMES PRINGLE COCHRANE.

Witnesses:

ROBERT FRANCIS HUTCHISON,
LAURA WILSON GRAY.
